RESISTANCE SOCKET FOR SIGNAL LAMPS

Edmond F. Webb, Franklin Village, Mich., assignor to Chrysler Corporation, Highland Park, Mich., a corporation of Delaware

Application April 22, 1942, Serial No. 440,059

4 Claims. (Cl. 201—63)

This invention relates to an improved light bulb socket and resistance element assembly.

One of the main objects of the invention is the provision of an assembly of this kind which is detachably securable to a vehicle instrument panel or a similar support and in which the socket and resistance element portions are axially aligned and in which the latter is disposed remote from the instrument panel.

Another object of the invention is the provision on the socket portion of an assembly of this kind of a resistance element supporting member which also serves as a shield for a conductor wire that leads to one of the contacts of the socket portion.

A still further object of the invention is the provision on a socket of this character of a resistance element supporting structure which further serves as the mounting for a terminal with which another conductor wire may be connected.

An embodiment of the invention is illustrated in the drawing in which:

Fig. 1 is a side elevational view, partly in section, of a lamp socket and resistance element assembly embodying the invention.

Fig. 2 is a right end view of the socket and resistance element assembly shown in Fig. 1.

Fig. 3 is a fragmentary, longitudinal view taken on the line 3—3 of Fig. 1.

In the drawing is illustrated an embodiment of the invention in a detachable lamp of the type used on automobile instrument panels. The lamp comprises a tubular body portion 10 having an outwardly extending radial flange 11 at its left end, as viewed in Fig. 1. Mounted on the latter end of the tubular body 10 is a disc 12 having outwardly extending angular tongues 13 which are sufficiently resilient to deflect in order to accommodate insertion of the tongues 13 through an aperture 14 in a support 15. The disc 12 is clampingly engaged on the flange 11 by a collar 16, of U-shaped cross section. In order to securely seal the disc and tubular body 10 together compressible washers 17 are disposed on opposite sides of the flange 12. A compressible sleeve 18 is also disposed within the webbed portion of the channel shaped collar 16. The washers 17 and sleeve 18 preferably comprise rubber, fibre or the like.

The left end portion of the tubular body part 10 is provided with a bayonet slot 19 which is adapted to cooperate with a lug 20 on a lamp bulb 21 that is receivable in the left socket end portion of the tubular body part 10 in a conventional manner. A terminal member 22 is axially

slidably mounted in the right end portion of the body part 10 and provided with a contact element 23 which is engageable with an end contact element 24 of the bulb 21. The terminal member 22 is yieldably urged leftwardly, as viewed in Fig. 1, by a spring 25 which bears between a shoulder on the terminal member and a flange 26 formed on the right end portion of the tubular member 10 and which extends inwardly substantially radially of the tube.

A sheet metal sleeve 27 extends through an opening 28 in the right end of the tube 10 which is surrounded by the edge of the flange 26. The sleeve 27 has an outwardly extending radial flange 29 located within the tube 10 and contacting with the internal side of the flange 26 thereon. Formed on the opposite extremity of the sleeve 27 is a radially outwardly extending flange 30. A resistance element 31, preferably comprising a ring shaped carbon block, is disposed around the sleeve 27 and electrically insulated therefrom by a tubular insulating member 32 disposed between the outer surface of the sleeve 27 in the wall of the central passage of the carbon ring 31 in which the sleeve 27 is received. The left side face 33 of the resistance element 31 is firmly held in electrical contact with the external side of the flange 26 by clampingly engaging the resistance element 31, a sheet metal contact member 34 and a yieldable electrically insulating washer 35 between the flange 30 of the sleeve 27 and the flange 26 of the tube 10. The terminal member 24 has a disc shaped body portion provided with an aperture 36 for receiving the sleeves 27 and 32 and it is provided with an outwardly extending ear 37 to which is attached a bracket 38 having a tubular part 39 adapted for attachment to, and electrical contact with a conductor 40.

Electrical current is supplied to the bulb 31 through the foregoing assembly in the following manner: an electrical circuit is established from the conductor 40, through the bracket 28, terminal element 34, carbon resistor 31 and tubular body portion 10 to the side wall of the base portion of the bulb 21. Electrical current is supplied directly from the contact 23 to the contact 44 of the bulb. The carbon resistor 31 serves to reduce the intensity of the current supplied to the bulb. The assembly is particularly advantageous in a system such as that used in an automobile where certain illuminating devices require more current than others.

Although but one specific embodiment of the invention is herein shown and described, it will

be understood that various changes in the sequence of operations, steps and materials employed may be made without departing from the spirit of the invention.

I claim:

1. A lamp socket and resistance element assembly including a socket portion comprising a sheet metal tubular casing having on one end a lamp bulb receiving opening and means for detachably mounting said assembly on a support, a sleeve extending axially from the opposite end of said casing having a passage communicating with the interior of the latter for accommodating a conductor wire, and a resistance element mounted on and surrounding said sleeve and having an outwardly extending flange on the end thereof remote from said casing, a resistance element mounted on and surrounding said sleeve, and a terminal unit comprising a mounting disc disposed between said latter flange and said resistance element and having means thereon for connection with a second conductor member.

2. A lamp socket and resistance element assembly including a socket portion comprising a sheet metal tubular casing having on one end a lamp bulb receiving opening and means for detachably mounting said assembly on a support, a metal sleeve extending axially from the opposite end of said casing having a passage communicating with the interior of the latter for accommodating a conductor wire and having an outwardly extending flange on the end thereof remote from said casing, a layer of electrical insulating material surrounding said sleeve, a resistance element mounted on said sleeve and electrically insulated therefrom by said material, said element being in electrical contact with the end of said casing, a terminal unit comprising a metal mounting disc disposed between said flange and said resistance element and having electrical contact with the latter and an electrical insulating washer between said disc and said flange, said flange being so constructed and arranged as to firmly hold opposite extremities of said resistance element in electrical contact with said casing and said disc respectively.

3. A lamp socket and resistance element assembly including a socket portion comprising a tubular sheet metal casing having a lamp bulb receiving opening at one end and an inturned

flange at its opposite end, a sleeve extending axially from said flanged end of said casing having an outwardly extending flange within the latter and abutting the internal side of said first

5 mentioned flange in interlocking engagement therewith, a solid type resistance element mounted on and surrounding said sleeve having an extremity in abutting engagement with said first mentioned flange, and an outwardly extending flange on the end of said sleeve remote from said casing and adjacent the opposite extremity of said resistance element for simultaneously urging the latter against the flange of said casing and retaining the last mentioned flange in 10 clamped engagement between said resistance element and the first mentioned flange of said sleeve.

4. A lamp socket and resistance element assembly including a socket portion comprising a 15 tubular metal casing having a lamp bulb receiving opening in one end and an inwardly extending substantially radial flange on its opposite end, a metal sleeve extending axially from the flanged end of said casing having an outwardly 20 extending substantially radial flange within the latter and abutting the internal side of said flange of said casing in interlocking engagement therewith, said sleeve having an outwardly extending substantially radial flange on its opposite 25 extremity, a layer of electrical insulating material surrounding said sleeve, a ring-shaped carbon resistance element mounted on said layer between said last mentioned flange and said casing and electrically insulated from said sleeve, 30 a terminal unit comprising a metal mounting disc concentrically mounted on said sleeve in contact with the end of said resistance element remote from said casing, and a washer comprising electrical insulating material between 35 the flange of the free end of said sleeve and said mounting disc, said flange of the free end of said sleeve being so constructed and arranged as to firmly hold opposite extremities of said resistance element in electrical contact with said casing and mounting disc respectively and to retain the 40 flange of said casing in clamped engagement between said resistance element and the flange of the adjacent end of said sleeve.

EDMOND F. WEBB.
